UNITED STATES PATENT OFFICE.

CONRAD NORDFORS, OF JERSEY CITY, NEW JERSEY, ASSIGNOR TO WOOD NEWSPAPER MACHINERY CORPORATION, OF NEW YORK, N. Y., A CORPORATION OF VIRGINIA.

MACHINE FOR COUNTING OUT AND MARKING PRINTED PRODUCTS.

1,421,983.

Specification of Letters Patent.

Patented July 4, 1922.

Application filed December 11, 1918. Serial No. 288,211.

To all whom it may concern:

Be it known that I, CONRAD NORDFORS, a citizen of the United States, residing at Jersey City, in the county of Hudson and 5 State of New Jersey, have invented a new and useful Machine for Counting Out and Marking Printed Products, of which the following is a specification.

The object of this invention is to provide 10 means whereby a predetermined number of printed products, as for example newspapers, can be counted out and an identification mark placed upon the last one of each lot, so that they can be gathered into uniform bundles, and more especially to provide a simple and inexpensive device for this purpose. Further objects and advantages of the invention will appear hereinafter.

20 Reference is to be had to the accompanying drawings, in which—

Fig. 1 is a view showing a part of the folder of a press with a preferred embodiment of this invention shown in its proper 25 position relative thereto;

Fig. 2 is a similar view of the counting and marking mechanism on enlarged scale;

Fig. 3 is an end view of the same;

Fig. 4 is an end view of the folder illustrating the preferred position of the mark 30 on the web, and

Fig. 5 is a view of the marked copy.

It is the ordinary practice to deliver newspapers and certain other printed products 35 on slow running belts. This forms an extended pack and the papers are divided off into bundles of fifty by causing each fiftieth paper to protrude slightly beyond the rest so that the operators can pick up exactly 40 fifty papers at each operation. It has been found in practice, however, that when mechanical belts or wire carriers are used the mechanical separation is usually lost during the run to the mailing room. Thus 45 it is no longer possible for the operators to pick up a bundle of the desired size without recounting. This causes delay that cannot be tolerated in modern newspaper practice.

50 This invention is designed to permanently mark the paper at the end of each bundle, as for example the fiftieth paper, so that if it does get misplaced it can be identified at once and no time need be lost in locating it.

55 The means for protruding the fiftieth paper

beyond the pack can also be dispensed with if desired, although it is a simple mechanism and it is within the province of this invention to retain it.

Referring to the drawings I have shown 60 the invention as applied to a printing press having a folder supplied with a former plate 10 down over which the web passes. On the frame 11 I have shown a bracket 12 to which is secured by means of a clamp 65 13 an ink fountain 14.

On some shaft of the press which runs in synchronism with the printing cylinder, as for example the folding cylinder shaft 16, I attach a flexible shaft 17. I connect it 70 with a worm 18 mounted in bearings 19 at the bottom of the fountain 14 so that this worm shall rotate also in synchronism with the printing cylinder. This worm meshes with a worm wheel 20 and the relationship 75 between them is such that the shaft 21 on which the worm wheel 20 is mounted will make one revolution to fifty revolutions of the worm 18 and printing cylinder if the papers are to be separated into bundles of 80 fifty.

On this shaft 21 is mounted a fountain roll 22 provided with the usual scraping blade 23 slidably held in the fountain cover 24 and operated by a screw 25 to regulate 85 the amount of ink on the face of the ink fountain roll 22.

Pivoted on a shaft or stud 27 fastened to the fountain body is a ductor arm 28. This is held back toward the fountain roll 22 by a 90 spring 29 fastened to a pin 30 on the fountain. On the arm 28 is a shaft 31 which carries a ductor roller 32 and a cam roller 33. The cam roller is operated by a cam 34 fixed to the shaft 21 and of course rotating with it 95 at the rate of one rotation for every fifty papers delivered.

The ink fountain is located at the center of the former plate and it will be obvious that every time the fiftieth paper reaches the 100 proper position the cam 34 will come into position to move the ductor roller 32 over into the dotted line position in Fig. 2 and contact with the center folded margin of the web. This leaves a printed strip 40 on the 105 folded edge of each fiftieth paper. This is done while the web is running through the folder and provides a simple and accurate identification independently of the form of delivery used, of the speed of operation, and 110

of any misplacement of any of the papers on the delivery mechanism.

It will be understood, of course, that the ductor roller may come into contact with the running web for all or a part of the length of a paper so as to make a stripe throughout the length of the folded product or merely a spot as may be desired. Each fiftieth paper, therefore, can be identified from the edge as indicated in Fig. 5 without difficulty even though it may not project beyond the next paper. Of course it will be understood that if papers are to be removed in bundles of a different number than fifty, the relationship between the worm 18 and the worm wheel 20 will have to be changed accordingly and that the location of the striping device and the duration of its action may be arranged in accordance with the conditions existing in the press room and the kind of product that is being delivered.

Although I have illustrated and described only a single form of the invention, I am aware of the fact that many modifications can be made therein by any person skilled in the art without departing from the scope of the invention as expressed in the claims. Therefore I do not wish to be limited to all the details of construction herein shown and described, but what I do claim is—

1. The combination of the stationary former plate of a paper folder, with freely rotat-

able means movable to a position to press the web against said plate and adapted to be turned by the movement of the paper for marking the last one only of each series of products of a predetermined number, while passing over said plate.

2. The combination with a paper feeding device, of an ink fountain, a shaft in the ink fountain, a fountain roll on said shaft, a vibratory ductor roller normally out of contact with the paper in said feeding device and in contact with the fountain roll, and means for moving the ductor roller periodically out of contact with the fountain roll and into printing position.

3. The combination with a printing press having a shaft arranged to rotate in synchronism with its printing cylinder, of an ink fountain, a worm connected with said shaft to rotate with it, a worm-wheel in mesh with the worm, a shaft in the ink fountain to which said wheel is fixed, a cam and a fountain roll on said shaft, a vibratory ductor roller normally in contact with the fountain roll, and means cooperating with said cam for moving the ductor roller periodically into position to print on a product passing through the press.

In testimony whereof I have hereunto affixed my signature.

CONRAD NORDFORS.
